PIN-SETTING MACHINE

James T. Wheeler, Atlanta, Ga.

Application April 10, 1946, Serial No. 660,929

3 Claims. (Cl. 1-53)

1

This invention relates to hand machines designed for setting pins or the like, means being provided for advancing pins contained in a magazine forming a part of the body portion of the machine, to a position directly under the hammer, which operates to drive or set the pins.

An important object of the invention is to provide an operating handle and lever, operated by the handle for moving the pin-feeding mechanism, to deposit pins directly under the hammer, the pin-feeding mechanism being so constructed that only one pin will be released for positioning, with each operation of the handle.

With the foregoing and other objects in view which will appear as the description proceeds, the invention consists of certain novel details of construction and combinations of parts herein-after more fully described and pointed out in the claims; it being understood that changes may be made in the construction and arrangement of parts without departing from the spirit of the invention as claimed.

Referring to the drawings.

Figure 1 is a sectional view taken on line 1—1 of Fig. 2.

Figure 2 is a sectional view taken on line 2—2 of Fig. 1.

Figure 3 is a sectional view taken on line 3—3 of Fig. 2.

Figure 4 is an end elevational view taken approximately on line 4—4 of Fig. 3.

Figure 5 is a sectional view taken on line 5—5 of Fig. 3.

Referring to the drawings in detail, the body portion which is of tubular construction, comprises side members 5 and a bottom 6, the top of the body portion being indicated by the reference character 7.

The reference character 8 indicates the handle of the machine, by means of which the device is gripped, when in use.

Near the forward end of the handle 8 is an opening 9 through which the lever 10 extends, the lever 10 being pivotally supported on the ear 11 that extends forwardly from the handle, as clearly shown by Fig. 3 of the drawings.

The upper end of the lever 10 is bifurcated as at 12 and accommodates the pin 13 carried by the extension 14 of the actuating lever 15.

Rising from the top of the body portion are spaced plates 16, providing a support for the handle 17 which has pivotal connection with the plates, at 18. The handle 17 is connected with one end of the actuating lever 15, by means of the link 18, the connection between the link 18

2

and actuating lever 15, being spaced from the pivot point 19 of the actuating lever 15, so that when the link 18 is moved downwardly with the downward movement of the handle 17, the forward end of the actuating lever is elevated, for purposes to be hereinafter more fully described.

Pivotedly connected with the forward end of the actuating lever 15, is the arm 20 which is formed with a notch 21 adapted to engage with the shoulder 22 formed by the notch 23 of the hammer 24.

The hammer 24 is mounted in the hammer barrel 25 which has its lower end open, to communicate with the body portion of the machine.

Slot 26 is formed in the wall of the hammer barrel, and accommodates the arm 20, which moves therethrough. The arm 20 is held within the slot, by means of the spring arm 27 which has one of its ends bearing against the rear surface of the arm 20, the spring arm being coiled around the pivot point 19.

The hammer 24 is urged downwardly, by the coiled spring 28 which is compressed within the barrel 25, when the hammer 24 moves to the limit of its upward movement. The upper end of the hammer barrel 25 is closed by means of the removable cap 29, so that the hammer may be readily removed and replaced, should it become necessary to repair this mechanism.

Fitted within the forward end of the body portion, directly under the hammer barrel 25, is a block 30 which is secured in position, by means of the screws 31 that extend through openings in the body portion and are seated in threaded openings of the block. Formed integral with the block 30 is the bar 32 that extends rearwardly within the body portion, the free end of the bar 32 being extended beyond the end of the body portion.

The block 30 is formed with a barrel opening dispensed vertically of the block, the opening being designed to receive the barrel 33, which rotates therein, between the bottom 6 and top 7.

The inner side of the block 30 is formed with a slot 34 that communicates with the barrel opening, providing a guideway for the tape 35 in which the pins 36 to be set by the machine, are held. The pins 36 are held in spaced relation with respect to each other within the tape, and are so arranged that as the tape is fed through the machine, the pins will be directed into the longitudinal vertical grooves formed in the barrel 33, as shown by Fig. 2 of the drawings.

A horizontal groove 37 is formed in one side of the block 30, and this groove 37 intersects the barrel opening of the block 30. The groove pro-

vides a guideway for the spring arm 38 which has a lug 39 formed at its free end, the lug 39 being designed to engage within the grooves of the barrel 33 to move the barrel with each reciprocating movement of the arm 38. The arm 38 is provided with an opening through which the spring finger 40 extends, the spring finger being secured to the arm 38 in such a way that the lug 39 will be normally urged into engagement with the barrel 33.

Formed on the inner end of the spring arm 38, are spaced flanges 41 and 42 which flanges are vertically disposed and adapted to be engaged by the lower tapered end of the lever 10. For example, after the handle 17 has been operated to set a pin, and the handle is released, the handle 17 is moved upwardly to the position as shown by Fig. 1 of the drawings, whereupon the lever 10 engages the forward flange 41 as shown by Fig. 2, moving the spring arm 38 forwardly, resetting the arm in position to feed the successive fasteners below the driver upon the next actuation of the lever 17.

Due to the construction of the levers and arms, it will be obvious that when the handle 17 is depressed, the lever 10 will engage the flange 42, moving the arm 38 in the direction as indicated by the arrow in Fig. 3 of the drawings. With this movement, it is obvious that the barrel will be rotated to bring a pin directly under the hammer 24.

A setting pin indicated at 43 extends from the hammer 24 and is so located that it will pass through one of the grooves of the barrel 33, forcing the pin held within the groove, from the machine, setting the pin.

In the operation of the device, the hammer 24 is moved upwardly by the upward movement of the forward end of the actuating lever 15. As the arm 20 moves to the limit of its upward movement, the arm contacts with the upper end of the slot 26, causing the arm 20 to move to disengage the hammer 24, whereupon the hammer is snapped downwardly, under the action of the spring 28, setting the pin which falls directly under the setting pin 43.

It will of course be understood that the tape 35 in which the pins to be set are held, is fed forwardly by contact with the barrel 33, as the operation of the handle 17 is repeated.

What is claimed is:

1. In a pin-setting machine, a body portion, a vertically movable hammer mounted at one end of the body portion, a magazine for holding a pin tape, a vertical rotating pin barrel having vertical peripheral grooves disposed directly under the hammer, a spring arm slidably mounted with-

in the body portion, a lug at one end of the spring arm movable within the grooves rotating the pin barrel with each sliding movement of the spring arm moving a pin held in the pin tape to a position under the hammer for engagement by the hammer, spaced flanges extending laterally from the spring arm, an operating handle, a lever movable to engage the flanges reciprocating the spring arm, and means operated by the handle for setting the hammer and operating the lever.

2. In a pin setting machine, a body portion, a vertically movable spring-pressed hammer operating at one end of the body portion, a pivoted handle mounted on the body portion, a pin magazine within the body portion for holding a pin tape, a rotatable vertical barrel having longitudinal peripheral grooves located at one end of the body portion under said hammer, said grooves accommodating pins held within the pin tape positioned within the magazine, means for rotating the barrel a predetermined distance with each operation of the hammer, whereby a pin is fed under the hammer, said barrel rotating means including a lever operated by the handle, said lever moving the hammer upwardly against the tension of the spring, and a sliding member within the body portion operated by said lever, the sliding member engaging within the grooves rotating the barrel moving a pin directly under the hammer for driving by said hammer.

3. In a pin setting machine, a body portion, a pin magazine for holding a pin tape, within the body portion, a vertically movable hammer operating at one end of the body portion, a vertical rotating pin barrel mounted within the body portion under said hammer, said barrel having grooves into which pins held vertically within the pin tape are fed from the magazine, a reciprocating spring arm mounted within the body portion and engaging said barrel rotating the barrel with each reciprocation of the spring arm, whereby pins are moved directly under the hammer for striking engagement by the hammer to set the pins, a pivoted handle mounted on the machine, and means actuated by the handle for reciprocating the spring arm.
